UNITED STATES PATENT OFFICE.

ALBERT C. FISCHER, OF CHICAGO, ILLINOIS.

RAIL FILLER.

No Drawing.

Application filed December 12, 1925. Serial No. 75,151.

With the growth of large cities the importance of providing expansion and contraction and sound deadening of the rails of surface car lines is becoming more essential.

It is necessary that the product formed as a filling means for the rails be economical and at the same time have insulating value as well as functioning as an expansion joint.

My invention relates to an economical product produced from ground corn cobs mixed with a binding material. Said binding material may be composed of bituminous material or a bituminous material having intermingled therewith divided fibrous material for reinforcing the same. The bituminous material is prepared in a heated state in suitable mixing devices, known to the art, and adding thereto the ground corn cobs and finely divided reinforcing fibre, or the bituminous material may have incorporated therein finely divided fibrous material reduced to a heated state and then having mixed therein ground corn cobs.

A suitable formula for said mixture would consist of thirty-five (35) per cent ground corn cobs, fifty (50) per cent bituminous material and fifteen (15) per cent finely divided fibrous material.

It may readily be understood that these proportions can be modified and that the formula need not necessarily be committed to any particular type of fibrous material. The principal ingredient and filler consists of ground corn cobs and bituminous material, the ground corn cob preserving its insulating value throughout the mixture, that

is to say the soft pithy corn cob fibre materially aids the bituminous material in deadening sound by insulating the rails from the hard roadbed, the other fibrous material acting to strengthen the composition. When moulded to form or pressed into shape the filler is readily adapted to be inserted in the rail, where it acts as an expansion joint and deadens the sound of the passing traffic.

The shape of this mixture depends upon the contour of the rail, but the form is that of the form of the contour of the rail on one side and a straight, vertical face on the opposite side.

This rail joint is provided in three to five foot lengths, and varies from one to three inches in thickness.

My invention is not limited to the shape or dimension, but is sufficiently broad to cover any form of material which may be used as a sound insulator, and which can also be used as an expansion joint.

I claim:

1. A rail filler of the class described, comprising a preformed block-like member comprising a homogeneous mixture of bituminous material and ground corn cob.

2. A rail filler of the class described, comprising a preformed block-like member comprising a homogeneous mixture of bituminous material, ground corn cob and strengthening fibres.

Signed at Chicago, Illinois, this 10th day of Dec., A. D. 1925.

ALBERT C. FISCHER.
